CLAIM

The ornamental design of an ammunition belt feed assembly, as shown and described.

DESCRIPTION

FIG. 1 is a perspective view from a first side of the ammunition belt feed assembly.

FIG. 2 is a perspective view from an opposite side of the ammunition belt feed assembly.

FIG. 3 is a top view of the ammunition belt feed assembly.

FIG. 4 is a perspective view showing the first arm separated from the second arm of the ammunition belt feed assembly.

FIG. 5 is a front view showing the first arm separated from the second arm of the ammunition belt feed assembly; and, FIG. 6 is a front view of one arm of the ammunition belt feed assembly in position of use on a firearm which is shown in broken lines to illustrate the environment of the claimed design and forms no part thereof.
